CLAIM

I claim the ornamental design for a bottle, as shown and described.

DESCRIPTION

FIG. 1 is a top, front, and right side perspective view of a bottle, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a cross-sectional view thereof, taken along line 8-8 of FIG. 2; and,

FIG. 9 is a cross-sectional view thereof, taken along line 9-9 of FIG. 6.

The bottle is entirely transparent, and the oblique line shading in the drawings indicates the transparency of this design. The opposing side details of the bottle as they would be seen through the transparent sidewall material have been omitted for ease of understanding. The thin lines shown in the drawings indicate the three-dimensional surface shape of the bottle.

1 Claim, 8 Drawing Sheets
